UNITED STATES PATENT OFFICE.

CHARLES L. WIGHT, OF MAHUKONA, HAWAII.

FRUIT-JAR.

SPECIFICATION forming part of Letters Patent No. 480,537, dated August 9, 1892.

Application filed August 1, 1891. Renewed July 11, 1892. Serial No. 439,567. (No model.)

To all whom it may concern:

Be it known that I, CHARLES L. WIGHT, of Mahukona, Hawaii, have invented a new and Improved Fruit-Jar, of which the following 5 is a specification, reference being had to the annexed drawings, forming a part thereof, in which—

Figure 1 is a side elevation of my improved fruit-jar. Fig. 2 is a plan view. Fig. 3 is a 10 vertical transverse section taken on line $x-x$ in Fig. 1, parts being broken away to show the tenons on the corner-posts and the sockets or holes therefor in the cover and bottom. Fig. 4 is a horizontal section taken on line $y-y$ in Fig. 1, and Fig. 5 is a vertical transverse 15 section of a modified form.

Similar letters of reference indicate corresponding parts in all the views.

The object of my invention is to construct 20 a jar for the preservation of fruit, honey, butter, &c., which may be inexpensively made, is not liable to breakage, and which is formed of parts which may be shipped in a knock-down state and assembled at the place of use.

25 My invention consists in the construction and arrangement of parts, as will be herein-after described and claimed.

The base-board A is formed of any suitable wood or analogous material which will 30 absorb a waterproofing substance, such as paraffine. In the board near the corners are formed holes a for receiving the tenons of the corner-posts B. The posts B are preferably made rectangular in cross-section and 35 are provided in two of their adjoining faces with grooves b for receiving the glass sides C, which also extend downwardly into the grooves c in the base-board A. The upper ends of the corner-posts B are provided with 40 tenons which are received in holes in the cover D, the said cover being also provided with the grooves d for receiving the upper edges of the glass sides C. The cover D, which is made of the same material as the 45 base-board, is provided with a groove f in the upper surface thereof. To the cover D is fitted a metallic cap E, provided with downwardly-projecting ears g , which enter into the groove f .

50 In Fig. 5 is shown a modification in which the glass sides C are inclined outwardly at the

top, thereby making a flaring jar, as shown. The joints are rendered tight by a suitable cement—such, for example, as shellac or paraffine softened by the addition of vaseline. 55

After the body of the jar is assembled and filled the cover is put in its place and cemented. The cap E is shipped with the jar, so that after the jar is opened by means of a can-opening tool inserted in the groove f the 60 cap may be used for closing the jar.

In carrying out my invention I do not limit myself to the use of wood, as I may employ any waterproof material or suitable material which may be waterproof or rendered waterproof; nor do I confine myself to the use of glass for the material of the sides, as I may use wood, metal, or porcelain for this purpose. 65

Having thus described my invention, I 70 claim as new and desire to secure by Letters Patent—

1. A knockdown jar or receptacle comprising a bottom having marginal grooves in its upper face and sockets or holes intersecting 75 said grooves, a cover having similar grooves and holes, corner-posts each having two longitudinal grooves and end tenons to enter the base and cover sockets, and the side panels, the longitudinal edges of which fit the 80 base and cover grooves and the vertical edges of the post-grooves, substantially as set forth.

2. A jar, formed of the grooved base-board A, provided with holes a , the corner-posts B, grooved longitudinally and provided with 85 tenons at opposite ends, the sides C, the cover D, furnished with grooves for receiving the sides and holes for receiving the tenons of the corner-posts and provided with the central opening e and groove f , and the cap E, 90 furnished with downwardly-projecting ears g , substantially as specified.

3. In a vessel of the character described, the cover having an annular groove f in its upper face to define its place of opening and 95 a closure of greater diameter than the groove and having downward-projecting ears entering the groove, substantially as set forth.

CHARLES L. WIGHT.
